CLAIM

The ornamental design for a gaming cabinet, as shown and described.

DESCRIPTION

FIG. 1 is a perspective view of a gaming cabinet showing our new design;

FIG. 2 is a front elevational view thereof;

FIG. 3 is a left side elevational view thereof;

FIG. 4 is a rear elevational view thereof;

FIG. 5 is a top plan view thereof; and,

FIG. 6 is a bottom plan view thereof.

The broken lines, which define the bounds of the claimed design, form no part thereof. Other broken lines representing the environmental structure are for illustrative purpose only and form no part of the claimed design.
